UNITED STATES PATENT OFFICE.

LOUIS V. ARONSON, OF NEWARK, NEW JERSEY.

NECKWEAR.

1,234,523.

Specification of Letters Patent. Patented July 24, 1917.

Application filed March 9, 1915, Serial No. 13,152. Renewed December 21, 1916. Serial No. 138,282.

To all whom it may concern:

Be it known that I, LOUIS V. ARONSON, a citizen of the United States, and a resident of Newark, in the county of Essex and State 5 of New Jersey, have invented certain new and useful Improvements in Neckwear, of which the following is a specification.

The invention relates to improvements in neckwear, more particularly to the type generally known as "stocks". Heretofore, with neckwear of this character it was not possible to obtain the so-called four-in-hand or the bow effect therewith owing to the fact that the tie portion thereof is sewed or otherwise 10 permanently attached to the stock portion. It is the object of the present invention to so associate the tie portion proper with the stock or collar portion that an adjustment or sliding motion between the same 15 is possible, permitting of a four-in-hand, bow tie or the like to be made in the usual manner.

In the accompanying drawings which illustrate the invention—

25 Figure 1 shows in perspective the improved stock tie in assembled position.

Fig. 2 is a plan thereof.

Fig. 3 is a plan of the stock or collar portion.

30 Fig. 4 is a detail fragmentary view illustrating the manner of assembling the tie for use.

Similar characters of reference designate corresponding parts throughout the several 35 views.

Referring to the drawings, 11 designates the stock or collar portion of the tie which is made of suitable width and may be provided for attachment with the usual button-hole 40 12 and loop 13 respectively at the front and rear thereof, if desired. The stock is provided, furthermore, with a narrow transverse slit 14 or equivalent means at one end

and through which the other end 15 of the tie, somewhat tapered for the purpose, is 45 adapted to be passed (Fig. 4) as heretofore.

This narrowed end 15, however, is provided with a transverse narrow slit 16 or equivalent means through which a tie member 17 may be passed, and which member 50 may be of the four-in-hand type shown herein, by way of example, bow type or any other suitable form. The same is not securely attached to this end 15 as formerly, but the narrow neck band 18 thereof is arranged to slide through the said slit 16. This will enable the tie 17 to be suitably 55 shifted or drawn therethrough to allow the desired form of tie to be made, said portion 18, moreover, serving to lock the stock 11 60 against separation. Not only, therefore may various forms of ties be thus worn in connection with the stock, but the use of various combinations of color or material therewith is possible. The improved neck- 65 wear also lends itself more readily to laundering as the two parts thereof are readily separated.

I claim:

1. Neckwear, comprising a stock or collar 70 member provided at one end with a slit and having its other end narrowed to pass through said slit, and a tie member attachable to the free end to slide therethrough.

2. Neckwear, comprising a stock member 75 provided with transverse slits at its opposite ends through one of which one end of the stock is adapted to be passed, and a tie member slidable through the other slit.

Signed at Newark, in the county of Essex, and State of New Jersey, this 6th day of March, A. D. 1915.

LOUIS V. ARONSON.
